COLLAPSIBLE CABINET

Louis Cummings, Weehawken, N. J.

Application May 4, 1949, Serial No. 91,307

1 Claim. (Cl. 312—262)

1

This invention relates to a collapsible cabinet. One of the principal objects of this invention is the provision of a collapsible or foldable cabinet which may be prefabricated in all of its parts, assembled at the factory, folded for shipment from the factory to the distributor and from the distributor to the consumer, and unfolded and set up by the consumer either at his home or at his place of business or at any other appropriate location, without the aid of tools or fastening members of any kind. Shipping costs of conventional cabinets are completely out of proportion to their selling price. Shipping costs are particularly too high insofar as mail order houses are concerned, since their business requires individual shipments of a single cabinet to a given customer or, at best, a very small quantity of cabinets to a given customer.

The collapsible or foldable cabinet of the present invention comprises, essentially, a plurality of parts which are hingedly connected to each other and means to hold said hingedly connected parts in predetermined relationship. More specifically, the collapsible or foldable cabinet herein described and claimed comprises a plurality of hingedly connected walls and doors and cover, shelf, and floor members to hold the walls in predetermined relationship. When the cabinet of the present invention is folded flat for packing and shipping purposes, it occupies a shipping space which is only a small fraction of the shipping space which conventional cabinets of the same size occupy. Shipping costs are correspondingly reduced. When the cabinet of the present invention arrives at its destination, that is at the home or place of business of the consumer, it may be unfolded and set up by the consumer without any trouble whatsoever, without any great skill and without the use of tools or fastening elements of any nature. When the cabinet is fully set up for use, it looks like any conventional cabinet of the same general type and it may be used in precisely the same manner as conventional cabinets are used. Should it be desired to move the cabinet from one place to another after it has been fully set up, it may be disassembled in the sense of removing its cover, shelf and floor members and it may then be folded to collapsed condition. The work of taking the cabinet apart and to fold it is no more complicated than to unfold it and to set it up.

Another principal object of this invention is the provision of a foldable or collapsible cabinet of the character described which is of exceedingly simple and inexpensive construction and which

2

may be fabricated in any machine shop having stamping and forming facilities. All of the major parts of this cabinet, that is the side and back walls, the door or doors, the top cover, shelf and floor members, are stamped out of sheet metal and their respective edges are formed or bent in appropriate fashion. Metal rods constitute the hinge pins or pintles by means of which the several walls and door or doors are hingedly connected to each other. It is not necessary to do anything to these rods but to cut them to proper length and to insert them into the hinge portions of the walls and door or doors. Their respective ends need not be disturbed in any way to prevent them from falling out of the hinge portions in which they are mounted, since they rest on the floor when the cabinet is set up for use. No machining, bolting, riveting, welding or spot welding is required to fasten the several parts together. Unskilled labor may be employed to assemble the several parts of the cabinet, since assembling means only the insertion of the rods into the hinge portions of the walls and door or doors.

A preferred form of this invention is shown by way of illustration in the accompanying drawing in which:

Fig. 1 is a perspective view of a two-door cabinet made in accordance with the present invention and fully assembled and set up, ready for use;

Fig. 2 is a horizontal section looking downwardly upon said cabinet and showing how the shelf and floor members are connected to the back and side walls of the cabinet;

Fig. 3 is a vertical section on the line 3—3 of Fig. 2, showing how the cover, shelf and floor members are mounted in the cabinet;

Fig. 4 is a perspective view of the top cover of the cabinet, looking upwardly at it;

Fig. 5 is a similar perspective view of the shelf of said cabinet, also looking upwardly at the shelf;

Fig. 6 is a perspective view of the bottom or floor member of the cabinet looking downwardly upon it;

Fig. 7 is a plan view showing how the three walls and two doors of said cabinet appear when they are spread out flat on a common plane; and

Fig. 8 is an enlarged fragmentary view in perspective of a portion of one of the side walls of the cabinet, showing a lug struck out therefrom to receive the shelf.

Cabinet 10, shown in Fig. 1, is illustrative of the many types of cabinet which may be con-

structed in accordance with the principles of the present invention. Cabinet 10 is a typical clothes cabinet with a shelf for hats, gloves, mufflers and the like. It is a two-door cabinet and again the use of two doors instead of only one is illustrative only of the invention.

Cabinet 10 has a back wall 11, a pair of side walls 12 and 13 respectively, and a pair of doors 14 and 15 respectively. Considering back wall 11 first, it will be seen that it comprises a rectangular sheet of metal of the type generally used in metal cabinet construction, the lower edge of said metal sheet being bent inwardly and upwardly to provide an upwardly extending flange 17 which is spaced from the main body of the metal sheet. The two side edges of said metal sheet are provided with a plurality of spaced projections which are curled or rolled to form hinge portions 18 and 19 respectively. The top edge is left untouched. Side walls 12 and 13 are folded over upon themselves along their respective top edges for added strength and rigidity. Their bottom edges are bent inwardly and then upwardly to form flanges 20 and 21 respectively, which project upwardly in spaced relation to the main body of the wall. Along their respective side edges, side walls 12 and 13 are provided with outwardly projecting portions which are curled or rolled to form hinge portions 23 and 24 respectively and 25 and 26 respectively. Doors 14 and 15 are also provided with hinge portions 28 and 29 respectively along one of their side edges. Door 15 is provided with a flanged top edge 30, a flanged bottom edge 31 and a flanged leading edge 32. Similarly door 14 is provided with a flanged top edge 33, a flanged bottom edge 34, and a flanged leading edge 35. The flanges on these doors contribute measurably to their strength and rigidity and they provide nicely finished edges which enhance the appearance of the cabinet and prevent injury to the hands. See Figs. 1 and 2. Hinged members 26 and 29 complement each other, as do hinge members 19 and 25, hinge members 18 and 24, and hinge members 23 and 28.

Walls 11, 12 and 13, and doors 14 and 15, may be hingedly connected to each other by simply slipping rods 40 into their respective hinged portions last above described. Piano type hinges are thereby provided between doors 14 and 15 and side walls 12 and 13 and also between said side walls and back wall 11. It is clear from the foregoing that the several walls and their two doors may be laid out flat in a common plane, as shown in Fig. 7 or they may be folded flat upon themselves, or they may be set up in the manner shown in Fig. 1.

Cabinet 10 also includes a top cover 41, a shelf 42 and a bottom floor member 43. It is these three members which hold the cabinet in the assembled or set-up condition shown in Fig. 1. Cover 41 comprises a rectangular piece of sheet metal whose back edge is turned downwardly to form a flange 45. The two side edges of said sheet metal are also turned downwardly and then folded upwardly to form double flanges 46 and 47 respectively. The front edge is also bent downwardly and then stepped or offset inwardly and then again bent downwardly to form a stepped flange 48. When the side walls of the cabinet are swung toward each other to their respective positions shown in Fig. 1, normal to the back wall, cover 41 may be laid upon said back and side walls in the manner shown in Figs. 1 and 3. Downwardly extending flanges 45, 46 and 47

project downwardly on the outside of walls 11, 12 and 13 respectively and thereby prevent the walls from swinging outwardly and away from each other. Thus far there is nothing to prevent the side walls from swinging inwardly toward each other. It is the shelf and the floor member which prevent such inward movement and they, of course, also assist in preventing the side walls from swinging outwardly from their respective positions as shown in Fig. 1.

Shelf 42 has four downwardly extending flanges 50, 51, 52 and 53 respectively along its front, back and side edges. It will be noted in Figs. 1, 2, 3, 7 and 8 that side walls 12 and 13 are provided with a plurality of upwardly projecting lugs 60 which are struck out of the sheet metal of which said side walls are made. These lugs 60 are arranged in rows of three, one row on each of said side walls, both rows being disposed at a common height above the floor and in predetermined spaced relationship to the cover 41. Shelf 42 may be placed upon said lugs 60 with its side flanges 52 and 53 respectively engaging said lugs and occupying the space between said lugs and said walls 12 and 13 respectively. When the flanges of shelf 42 are thus in engagement with the lugs of the side walls, it will be apparent that the shelf will fix the position of said side walls relative to each other and that it will prevent relative movement between them and between said side walls and the back wall.

Floor member 43 is also provided with downwardly extending flanges on all four side edges, to wit, back flange 62, side flanges 63 and 64 respectively and front flange 65. Front flange 65 is of a stepped nature, consisting of a downwardly extending portion, an outwardly bent horizontal portion, and a second downwardly extending portion which may be turned up along its lower edge for added rigidity. It will be recalled that the back and side walls are all provided with upwardly turned flanges 17, 20 and 21 respectively along their lower edges and that said flanges are spaced from the main body of said walls. It will become apparent therefore that downwardly extending flanges 62, 63 and 64 of the floor member may be inserted into the spaces between said flanges 17, 20 and 21 and their respective walls. This interlocking engagement of the flanges of the floor member with the flanges of the walls is best shown in Fig. 3. It will be clearly understood therefore that when the flanges of the floor member are in engagement with the flanges of the walls, relative movement between the two side walls and between said side walls and the back wall is thereby prevented.

The reason for the steps in front flanges 48 and 65 of the cover and floor members respectively, is best shown in Fig. 3. It will there clearly be seen that these stepped flanges accommodate the doors which nestle into their offset portions to bring the doors into flush relationship with the front edges of the cover and floor members. These stepped flanges also serve as stop members for the doors, preventing them from swinging inwardly beyond a predetermined point.

It will be appreciated from the foregoing that the back and side walls of the cabinet support the cover, that lugs 60 support the shelf and that flanges 17, 20 and 21 support the floor member. In return for such support, said cover, shelf and floor members hold the back and side walls of the cabinet in predetermined, fixed relationship, so that although no screws, bolts, welds or other

fastening means are used, the entire structure is strong and rigid in all of its parts. These observations of course do not apply to such accessories and hardware as the clothes hanging rod 70 and the door handles 71 and 72 respectively. Suitable bolts or rivets 75 are used to affix the clothes hanging rod to the bottom of shelf 42 and suitable screws 76 or other fastening members are used to affix said door handles to the doors. The doors may also be provided with snap catches or latches 77 and 78 respectively or with any other suitable latching or locking means.

The foregoing is descriptive of a preferred form of this invention and it will be clearly understood that this form may be modified in many ways and other forms may be had within the broad scope of the invention. By way of illustration, the upwardly turned flange on the bottom of the back wall may be eliminated, and reliance placed solely on the upwardly turned flanges of the two side walls. Lugs similar to those shown on the side walls may also be formed at the top of the back wall to engage the downwardly extending flange formed along the back edge of the cover member and thereby to prevent forward or backward shifting of the cover member. Other variations are possible within the broad scope of the present invention and especially should it be understood that the invention is not limited to the specific type of cabinet shown in the drawing.

The invention is defined in the following claim:

A collapsible cabinet comprising a unitary, sheet metal back wall, a unitary, sheet metal side wall on one side of said back wall, a unitary, sheet metal side wall on the opposite side of said back wall, and at least one unitary, sheet metal door, rolled hinge portions being formed along one vertical edge of the first mentioned side wall, integrally therewith, complementary rolled hinge portions being formed along the adjacent vertical edge of the back wall, integrally therewith, a pintle interengaging said hinge portions to join the first mentioned side wall to the back wall, rolled hinge portions being formed along the opposite vertical edge of the back wall, integrally therewith, complementary rolled hinge portions being formed along the adjacent vertical edge of the second mentioned side wall, integrally therewith, a second pintle interengaging the last mentioned hinge portions and the hinge portions on said opposite vertical edge of the back wall to join said second mentioned side wall to the back wall, rolled hinge portions being formed along the opposite vertical edge of the second mentioned side wall, integrally therewith, complementary rolled hinge portions being formed along the adjacent vertical edge of the door, integrally

therewith and a third pintle interengaging the hinge portions on the door and the hinge portions on said opposite vertical edge of the second mentioned side wall to join said door to said second mentioned side wall, inwardly and upwardly extending lugs being formed on the side walls a short distance below their respective top edges, inwardly and upwardly extending flanges being formed on said side walls along their respective bottom edges, a cover member which rests upon said back and side walls and has downwardly extending flanges which engage the outer surfaces of said back and side walls to prevent the side walls from swinging outwardly and away from each other on the first two mentioned pintles, a shelf which is disposed between said side walls and which rests upon their respective lugs, said shelf having downwardly extending flanges which project into the spaces between said lugs and the walls to which they are respectively connected, thereby preventing the side walls from swinging either inwardly toward each other or outwardly away from each other on said first and second mentioned pintles, and a floor member which is disposed between said side walls and which rests upon their respective upwardly turned flanges, said floor member having downwardly extending flanges which project into the spaces between said upwardly extending flanges and the walls to which they are respectively connected, thereby preventing said side walls from swinging either inwardly toward each other or outwardly away from each other on said first and second mentioned pintles.

LOUIS CUMMINGS.
